FIG. 1 is a front perspective view of the skull on dog tag shaped air freshener in accordance with our invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of a pair of skull on dog tag shaped air fresheners.

The broken lines shown in FIG. 8 are for illustrative purposes only and form no part of the claimed design.
